United States Patent

Des. 236,816
Patented Sept. 16, 1975

236,816

PRESSURE GAUGE

Clyde J. Martin, Cincinnati, Ohio, assignor to
Martin Industries, Inc.

Filed Mar. 20, 1974, Ser. No. 452,903

Term of patent 14 years

Int. Cl. D10—04

U.S. Cl. D10—85

FIG-1

FIG-2

FIG-3

FIG-4

FIG-5

FIG. 1 is a perspective view of a pressure gauge showing my new design;

FIG. 2 is a rear elevational view thereof;

FIG. 3 is a left side elevational view thereof;

FIG. 4 is a top plan view thereof; and

FIG. 5 is a bottom plan view thereof.

I claim:

The ornamental design for a pressure gauge, as shown.
